UNITED STATES PATENT OFFICE

FRANK E. PFEIFFER, OF DAYTON, OHIO, ASSIGNOR TO THE EGRY REGISTER COMPANY,
OF DAYTON, OHIO, A CORPORATION OF OHIO

AUTOGRAPHIC REGISTER

Application filed April 16, 1931. Serial No. 530,462.

This invention relates to autographic registers, and has for its object to provide a register of the pull type, in which the sheets of paper are grasped by the fingers of the operator and pulled out.

It is particularly the object of this invention to provide a writing table having a slot therein, through which the sheets of paper pass, and on the table adjacent the slot is a frame adapted in one position to hold the sheets of paper against the under side of the table, and in another position to move the sheets of paper so that they are substantially in alignment with the slot for being pulled through the slot.

It is also an object of this invention to provide means for operating the frame, either at the front or rear.

It is also an object of this invention to provide, in connection with the cover extending over the writing table, a hinged cutter plate, and means for elevating the cutter plate and for operating the frame when it is desired to remove the sheets of paper or withdraw them from the register.

It is also an object of this invention to provide, in connection with a fixed cover member and the writing table and a hinged cover, slots therein through which the sheets of paper may be gripped by the fingers of the operator.

It is my object to provide a very cheap and simple swinging frame pivoted beneath the writing table, having one bar for so holding the paper that the transverse creases or series of fine perforations will engage against the edge of the writing table for alignment purposes; and the other bar, when properly moved, will engage the paper so that the creases or transverse series of perforations will slip off of the edge of the writing table and permit the paper to be withdrawn over the writing table.

These and other advantages will appear from the following description taken in connection with the drawings, in which there is shown a preferred embodiment of this invention.

Referring to the drawings:

Figure 1 is a top plan view of one form of the autographic register.

Figure 2 is a vertical section through the front end of the casing of the autographic register, showing the cover and the writing table in elevated position and partly broken away.

Figure 3 is a longitudinal section through the register, showing the means for operating the rack for permitting the delivery of sheets of paper.

Figure 4 is a view showing the inside of the writing table in elevated position.

Figure 5 is a longitudinal section through the autographic register, showing the frame in a position to hold the sheets of paper against delivery.

Figure 6 is a top plan view of a slightly modified form of autographic register, in which there is a storage compartment for tickets.

Figure 7 is a top plan view of the register shown in Figure 6, with the cover and the writing table partly broken away.

Figure 8 is a longitudinal vertical section through the form of autographic register shown in Figure 6.

Figure 9 is an enlarged view of the upper central part of the register as shown in Figure 8, but showing the frame in a position for permitting the removal of sheets of paper from the register.

Figure 10 is a section through one part of the autographic register, showing in top plan view a modified form for operating the paper control frame.

Figure 11 is a side elevation of the parts shown in Figure 10.

In this register there is shown the usual casing having sides 1, a front end 2 and a rear end 3. Suitably attached to the sides of the casing, adjacent the front end, is a table 4, to the front end of which are attached ears 5 for pivotally supporting the table on a rod 5 which extends through the casing from one side to the other.

When the table is in closed position the rear end rests upon studs 7, two of which are on each side of the casing. However, any number of these studs may be provided.

There is also provided between the sides of the casing, supports in the form of rods 8. On the rear end of the writing table is a pressure plate 9, between which and the table the sheets of paper pass as they are being withdrawn. This pressure plate tends to hold the sheets of paper so that they will not buckle. This pressure plate and the rear end of the table have a rectangular cut-out part 10, which permits the advancing ends of the sheets of paper to be gripped by the fingers for removing them from the register.

Adjacent the front end of the writing table there is a narrow paper slot 11, through which the sheets of paper are fed onto the top of the table. For the purpose of controlling the delivery of sheets of paper through the slot 11 a frame is provided, which has a transversely extending bar 12, at each end of which is a right-angular wing 13, which terminates in a trunnion 14 in a line parallel with the bar 12. There are two of these trunnions supported underneath the table by clips 15 so that the frame may easily rock therein. Attached to the wings 13 in some suitable manner and slightly removed from the guide bar 12, is a guide bar 12a. The guide bar 12 holds the paper up near the under surface of the writing table during the writing period. When the frame is shifted the bar 12a brings the sheets of paper so that they may be removed through the slot 11.

Extending from one of the trunnions is an arm 16, substantially in the plane of the wings 13. Attached to the other trunnions is an arm 17, the purpose of which will be later described. Attached to the free end of the arm 16 is one end of a spring 18, which has its other end attached by some suitable means to the under side of the writing table.

When the table is closed and rests upon the studs 7 the frame is within the casing, with the spring 18 tending to hold the frame in its most rearward position. For the purpose of shifting the frame there is located on one side of the casing and within the casing a slide bar 19, which has a slit 20 therein through which a screw 21, or some other guiding means, passes and is supported by the wall of the casing. On the end of this slide bar is an abutment 22 adapted to engage the arm 17 of the frame for moving the arm toward the front of the casing when it is desired to remove the sheets of paper from the casing.

Attached near the rear end of the casing and to one side thereof is an arm 23, which has a shaft 24 attached at one end to one end of the arm and extending through one side of the casing. To the other end of the frame the slide bar 19 is pivotally attached, as indicated by the numeral 25. On the shaft 24 without the casing is an operating lever 26. When this lever is operated it causes the slide bar 19 to move and forces the abutment 22

against the arm 17 so that the frame is moved from this rearward position against the under face of the writing table to a position shown in Figure 3 for the removal of strips of paper from the casing.

Extending over the paper slot 11 is a pressure plate 27 attached to the writing table in front of the slot. This plate cooperates with the writing table at the rear edge of the slot for controlling the feeding or delivery of the sheets of paper from the casing. There is also provided, in connection with the casing, the usual cover 28, which has extending from the rear end thereof ears 29, by which the cover is pivotally supported on the casing by means of a rod 30 which extends through the casing from side to side. In this cover is the usual writing opening 31.

The rear end of the writing table has a rectangular recess 32, which is substantially over the cut-out part 10 in the writing table so that the sheets of paper to be removed from the register may be easily gripped by the fingers of the operator. During the time the sheets of paper are not being removed the recess 32 is closed by means of a cutting blade 33, which is sharp on its rear edge for easily severing the sheets of paper. This cutting blade is attached to the cover by means of hinges 34, composed of two straps connected in the usual manner by a spindle or shaft 35. Between the two hinges is a spring 36, which tends to hold the cutting blade in the recess 32 so that it is in a position normally for severing the sheets of paper.

The spindle 35 is suitably attached in a permanent manner to the parts of the hinges attached to the cutting blade so that by rotating the spindle the blade may be elevated out of the recess 32. For the purpose of rotating the spindle for elevating the blade 33 there is provided on one end an arm 37, which is in line with the operating lever 26 so that when this lever is operated for shifting the frame that controls the feeding of the paper, the cutting blade is elevated so that its point is away from the paper and the recess is open.

A spring 38 is attached at one end to the slide bar 19 with its other end attached to the side of the casing for the purpose of holding the bar so that it will not press against the arm 17 on the frame. By means of the springs 18, 38 and 36 the parts of the autographic register are held in the position shown in Figure 5. When the parts are in this position the sheets of paper cannot be withdrawn from the register, and in order to shift the parts so that the sheets of paper may be withdrawn the lever 26 is operated, forcing the frame toward the front of the casing, elevating the blade 33, after which the strips of paper may be withdrawn. After the paper has been withdrawn the desired

length the handle is released, and all of the parts again assume the position shown in Figure 5. Figure 3 shows the parts in sheet feeding position.

5 For the purpose of holding the cover in a closed position there is provided on each side of the casing a hook 39. The hinged cover substantially covers all of the casing shown in Figure 1 except a small part of the rear end, which is covered by a fixed cover member 40 forming an extension of the rear end of the casing. In this fixed cover member is a finger hole 41, through which the finger may be extended for gripping the advanced 10 ends of the sheets of paper for removing them from the register.

In Figures 6 to 11, inclusive, a slightly modified form of casing is shown, and a modified means for operating the paper control frame. In this form the same characters are used to designate the ends and sides of the writing table cover and the paper control frame, and all parts that are similar to those shown in Figures 1 to 5, inclusive. In 15 Figure 6 there is shown a modified form of slide bar for shifting the paper control frame. In this form the bar is indicated by the numeral 19a, which has therein guide slots 20a, in each of which is a guide pin or screw 21a supported by one side of the casing.

This bar is held in its rearward position by means of a spring 38a, which acts in the same manner as spring 38 does. This bar has on its front end an abutment for engagement 25 with the arm 17. This bar is operated by a handle 42, which extends through a slot 43 in one side of the casing. When it is desired to shift the paper control frame for removing the strips of paper the handle is moved toward the front of the casing.

In Figures 10 and 11 a slightly modified form of frame shifting means is provided. In these figures the arm 17 is extended into an arm 17a, which extends through a slot in 35 one side of the casing and has thereon a handle 42a. This handle extends through the slot 43, which is arcuate, as shown in Figure 11. In the form shown in these two figures the handle 42a is pressed down, thereby removing the frame from adjacent the under side of the writing table to a substantially vertical position so that the sheets of paper may be removed.

In the front end of the casing there is provided a paper box 44, from which the sheets of paper are fed through the slot 11. After the strips of paper have been withdrawn and severed, all or part of them may be inserted through a slot 46 into a compartment 47, 55 where they are preserved. This compartment 47 extends rearwardly from the part of the casing described and shown in connection with Figure 1, and has a more extended top or cover 40a, which is held to the casing by means of a lock 45.

On one side of the casing is a carbon compartment 48 adapted to carry a plurality of sheets of carbon paper. In this compartment, for supporting the sheets of carbon paper, is a shaft 49. The sheets of carbon paper are indicated by the numeral 50. In order to hold the free ends of the sheets of carbon paper there is provided on the side of the casing opposite the carbon compartment a lock bar 51, suitably pivoted to the side of the casing at one end and held at the other end by means of a lock or snap 52. The sheets of paper are indicated by the numeral 53 and have creases 54 therein. These sheets of paper are folded along the creases to form a stack, as shown in Figure 8, from which the strips of paper are fed through the frame between the bars 12 and 12a.

When the parts of the autographic register are in the position shown in Figure 5 the sheets of paper are in a position to receive writing thereon through the writing opening. When the paper control frame is in the position shown in this figure the strips of paper cannot be withdrawn, because of the angular nature of the straps engaging the writing table at the rear of the slot 11. When it is desired to withdraw the strips of paper from the register the lever 26 is moved toward the front end of the register, thereby raising the cutting blade 33 and moving the paper control frame toward the front so that the strips of paper may be more easily withdrawn through the slot 11.

After the strips of paper have been withdrawn a sufficient length the lever 26 is released. The various springs controlling the operation of these parts bring them back to the position shown in Figure 5. Figure 3 shows the operating mechanism in position for withdrawing the sheets of paper from the register.

I desire to comprehend within my invention such modifications as may be embraced within my claims and the scope of my invention.

Having thus fully described my invention, what I claim as new and desire to secure by Letters Patent, is:

1. In an autographic register, a casing, a writing table therefor having a slot therein for the withdrawal of a strip of paper from the casing, and means in the casing adapted in one position, in cooperation with the table, to fold the strip to prevent its withdrawal and in another position to partially straighten the strip of paper so it can be withdrawn.

2. In an autographic register, a casing, a writing table therefor having a slot therein for the withdrawal of strips of paper from the casing, and means to control the withdrawal of said strips, said means including a pair of transverse movable bars, one bar adapted to prevent withdrawal of the strips

and the other adapted to position the strips so they can be withdrawn.

3. In an autographic register, a casing, a writing table adapted to support thereon a plurality of strips of paper being withdrawn from the casing, and adjustable means in the casing adapted in one position to hold the strips of paper bent towards the table to prevent the withdrawal thereof, and in another position to hold the strips of paper away from the table so they may be withdrawn.

4. In an autographic register, a casing, a writing table for said casing adapted to support strips of paper being withdrawn from the casing, cutter means at one end of the table for cutting the strips, means near the other end of the table to bend and hold the strips against withdrawal, and a single means to release the strip-holding means and raise the cutter means off the strips.

5. In an autographic register, a casing, a writing table on said casing adapted to support strips of paper being withdrawn from the casing, pivoted cutter means at one end of the table for severing the strips, pivoted means near the other end of the table to prevent the withdrawal of the strips, and common means for moving the cutting means from the strips and operating the pivoted means for releasing the strips.

6. In an autographic register, a casing, a writing table on the casing adapted to support strips of paper being withdrawn from the casing, a pivoted cutter means at one end of the table for severing the strips, a pivoted frame near the other end of the table engaging the strips normally holding the strips against withdrawal, and common means to raise the cutter means and rock the strip-holding means to release the strips.

7. In an autographic register, a casing, a writing table on the casing for supporting strips of paper withdrawn from the casing, movable cutter means at one end of the table for severing the strips, movable strip-control means near the other end of the table, spring means to hold the strip-control means against strips whereby the strips are held adjacent the under side of the table, and a common means for moving the cutter means from the strips and the strip-control means to move the strips away from the bottom of the table.

8. In an autographic register, a casing, a writing table on the casing for supporting strips of paper being withdrawn from the casing, movable cutter means at one end of the table for severing the strips of paper, rocking strip-control means near the other end of the table, said control means having a part to engage the strips to hold them adjacent the under side of the table, and another part to engage the strips to move them away from the under side of the table,

and a common means to move the cutter means and to rock the control means.

9. In an autographic register adapted to hold a strip of paper having creases therein at spaced intervals, a writing table having a slot therein for the withdrawal of the strip from the casing, a rocking frame member on the table within the casing engaging both sides of the strip for holding the strip against the under side of the table with the strip engaging the table in the slot along a crease to hold the strip against the under side of the table, and for holding the strip away from the under side of the table, and means to rock the frame member.

10. In an autographic register, a casing having a compartment for strips of paper, a writing table pivoted to the casing, said table having a slot adjacent one end for the withdrawal of strips of paper, and a notch at the other end, removable cutter means over the notched end of the table, a frame member pivoted to the table adjacent the slot, said frame member engaging the strips of paper to hold the strips against the under side of the table and to move the strips away from the under side of the table, and means to remove the cutter means and rock the frame.

11. In an autographic register, a casing having a compartment for strips of paper, a writing table pivoted to the casing, said table having a slot adjacent one end for the withdrawal of strips of paper, and a notch at the other end, removable cutter means over the notched end of the table, a frame member pivoted to the table adjacent the slot, said frame member engaging the strips of paper to hold the strips against the under side of the table and to move the strips away from the under side of the table, and means to remove the cutter means and rock the frame, said means comprising a lever adjacent the cutter means, and a link from the lever to the frame.

12. In an autographic register, a casing having a compartment for strips of paper, a writing table pivoted to the casing, said table having a slot adjacent one end for the withdrawal of strips of paper, and a notch at the other end, removable cutter means over the notched end of the table, a frame member pivoted to the table adjacent the slot, said frame member engaging the strips of paper to hold the strips against the under side of the table and to move the strips away from the under side of the table, and means to remove the cutter means and rock the frame, said means comprising a lever pivoted to the casing adjacent the cutter means, and a link from the lever to the frame.

13. In an autographic register, a casing having a compartment for strips of paper, a writing table for said casing, said table having a slot for the strips of paper adjacent one end and a notch at the other end, a cutter

adapted to overlie the notch, a strip-control frame on the under side of the table adjacent the slot, means to hold the frame adjacent the under side of the table so the strips cannot be withdrawn from the compartment, and means to raise the cutter and rock the frame to release the strips so they can be withdrawn.

14. In an autographic register, a casing having a compartment for strips of paper, a writing table for said casing, said table having a slot for the strips of paper adjacent one end and a notch at the other end, a cutter adapted to overlie the notch, a strip-control frame on the under side of the table adjacent the slot, means to hold the frame adjacent the under side of the table so the strips cannot be withdrawn from the compartment, and means to raise the cutter and rock the frame to release the strips so they can be withdrawn, said means comprising a lever-operating cutter and a link extending from the lever to the frame.

15. In an autographic register, a casing having a compartment for strips of paper, a writing table for said casing, said table having a slot for the strips of paper adjacent one end and a notch at the other end, a cutter adapted to overlie the notch, a strip-control frame on the under side of the table adjacent the slot, means to hold the frame adjacent the under side of the table so the strips cannot be withdrawn from the compartment, and means to raise the cutter and rock the frame to release the strips so they can be withdrawn, said means comprising a lever-operating cutter and a link extending from the lever to the frame and pivoted to the lever and slidably supported by the casing.

16. In an autographic register, a writing table therefor, a presser plate at one end of the table for guiding and holding strips of paper passing over the table, said table and plate having therein a finger notch for the withdrawal of the strips, and means located over the plate and the notch to sever the strips of paper.

17. In an autographic register, a writing table therefor, a presser plate at one end of the table for guiding and holding strips of paper on the table, said plate and table having therein a finger notch for the withdrawal of the strips, and a cutter pivotally located over the plate and the notch to sever the strips of paper.

18. In an autographic register, a writing table therefor, a presser plate at one end of the table for guiding and holding strips of paper on the table, said plate and table having therein a finger notch for the withdrawal of the strips, a cutter pivotally located over the plate and the notch to sever the strips of paper, and means on the table to raise the cutter away from the notch so the ends of the strips are exposed.

19. In an autographic register, a casing

adapted to contain strips of paper having transverse creases therein, a writing table having a notch at one end and a slot adjacent the other end for the withdrawal of strips from the casing, and a pivoted frame member engaging said strips and adapted to hold the strips adjacent the under side of the plate with the creases against the edge of the table in the slot, whereby the strips may be aligned and adapted to move the strips so they can be fed over the edge of the table.

20. In an autographic register, a casing adapted to contain strips of paper having transverse creases therein, a writing table having a notch in one end and a slot adjacent the other end for the withdrawal of the strips from the casing, a frame pivoted to the table adjacent the slot and engaging the strips, spring means operating on the frame to hold the strips adjacent the under side of the table with the creases against the edge of the table in the slot, whereby pulling of the strips may align them, and means to rock the frame to move the strips away from the under side of the table so they may be withdrawn through the slot.

21. In an autographic register, a casing having at one end a compartment for folded strips of paper, a writing table over said compartment having a slot therein through which the strips are withdrawn, a pivoted frame on said table adjacent the slot engaging the strips, a spring tending to hold the frame in one position with the strips adjacent the under side of the table, whereby the strips are held with the folds against the table at one side of the slot, an arm on the frame, and means extending through one side of the casing for operating the arm to move the frame away from the under side of the table, whereby the strips may be withdrawn.

22. In an autographic register, a casing, a writing table for said casing having a slot therein for the withdrawal of strips of paper from the casing, a frame pivotally supported by the table in the casing, said frame having a pair of members between which the strips pass, means tending to hold the frame and the strips adjacent the underside of the table to one side of the slot, an arm on the frame, and means on the arm extending through one side of the casing to move the frame from one side of the slot to a point beneath the slot.

23. In an autographic register, a casing, a writing table resting on the casing, a presser plate at one end of the table for guiding and directing strips of paper over the table, said table having a slot near one end for the strips and a notch at the other end in the table and the plate, a frame through which the strips pass pivoted to the table near the slot, means tending to hold the frame and the strips adjacent the under side of the table, a cover for said casing over the table, said

cover having a notch at one end extending substantially across the notched end of the table, a cutter pivoted to the cover in the notch therein for severing the strips of paper 5 at the end of the writing table, and means for raising said cutter and swinging the frame to a position substantially beneath the slot.

24. In an autographic register, a casing, a writing table resting on the casing, a presser 10 plate at one end of the table for guiding and directing strips of paper over the table, said table having a slot near one end for the strips and a notch at the other end in the table and the plate, a frame through which the strips 15 pass pivoted to the table near the slot, means tending to hold the frame and strips adjacent the under side of the table, a cover for said casing over the table, said cover having a notch at one end extending substantially 20 across the notched end of the table, a cutter pivoted to the cover in the notch therein for severing the strips of paper at the end of the writing table, and means for raising said cutter and swinging the frame to a position 25 substantially beneath the slot, said means comprising an arm attached to the cutter, an arm attached to the frame and a lever operatively connected to each of said arms. 90

25. As a new article of manufacture for 20 aligning paper, for use with a writing table, a swinging frame comprising a forward bar and a rear bar between which a plurality of paper sheets are threaded, and means for positioning said bar to hold said sheets with 25 the transverse perforations or scoring therein against the edge of a writing table to align said sheets so they will pass freely over a writing table. 95

26. In combination in an autographic register having a plurality of transversely folded 40 sheets folded along transverse score lines or perforations, a writing table having a rear edge over which the sheets pass from beneath the writing table to a point over the writing table, a swinging frame pivoted beneath said writing table adjacent said edge having a pair of spaced bars between which said sheets pass before passing over the writing table, and means of positioning said frame so that 45 one of said bars will hold the sheets so that the transverse creases or series of perforations in the sheets will engage the rear edge of the writing table and the other of said bars, when the frame is moved, will disengage said 50 sheets from the edge of the writing table, and means for actuating said frame. 100

27. In combination in an autographic register having a plurality of transversely folded sheets folded along transverse score 60 lines or perforations, a writing table having a rear edge over which the sheets pass from beneath the writing table to a point over the writing table, a swinging frame pivoted beneath said writing 65 table adjacent said edge having a pair of 105

spaced bars between which said sheets pass before passing over the writing table, and means of positioning said frame so that one of said bars will hold the sheets so that the transverse creases or series of perforations 70 in the sheets will engage the rear edge of the writing table and the other of said bars, when the frame is moved, will disengage said sheets from the edge of the writing table, means for actuating said frame, and yielding means engaging the top of said sheets as they pass between the yielding means and the rear edge of the table. 75

In testimony whereof, I affix my signature.
